INVENTOR
HENRY J. STEGEMAN

BY *Chas. E. Townsend*

ATTY.

UNITED STATES PATENT OFFICE.

HENRY J. STEGEMAN, OF FAIRFIELD, CONNECTICUT, ASSIGNOR TO THE HOLT MANUFACTURING COMPANY, OF STOCKTON, CALIFORNIA, A CORPORATION OF CALIFORNIA.

TRACTOR.

Application filed November 8, 1918. Serial No. 261,615.

To all whom it may concern:

Be it known that I, HENRY J. STEGEMAN, a citizen of the United States, and resident of Fairfield, in the county of Fairfield and State of Connecticut, have invented certain new and useful Improvements in Tractors, of which the following is a specification.

My invention relates to new and useful improvements in tractors such as are used for drawing loads over the road and particularly for drawing agricultural instruments in the field.

The invention further refers to what is commonly known as a track-laying tractor, having four wheels and a sprocket chain connection, that travels around the pair of wheels upon each side to form a traveling tread upon which the wheels are supported.

More particularly the present invention is concerned with equalizing means, such as, for example, is shown in U. S. Patent No. 1,844,360, dated June 22nd, 1920, to William Turnbull. In said Turnbull patent the track-laying units are pivoted at one end to the main frame for rocking movement in a vertical plane and an equalizer bar connects the opposite ends of the track laying units together, and, in turn, is pivotally connected centrally to the main frame, so that the weight of the main frame is equally distributed on opposite track-laying units, and each unit is free to move vertically to conform to unevenness in the ground without unduly disturbing the position of the main frame. For convenience this is termed a three-point suspension, since the main frame is supported at two points in the rear and at one point in the front.

In the present invention I provide novel suspension means having four points of support, two of which are floating, the two floating points being connected together by novel equalizing means, whereby to give greater stability to the main frame and rigidity to the track-laying units, and to provide for a more even distribution of the weight of the main frame on the opposite track-laying units when the latter are rocked relatively. The present invention is of special importance in connection with extremely large tractors, such as are intended for carrying heavy guns.

With these and other objects in view the invention resides and consists in the construction and novel combination and ar-

angement of parts hereinafter more fully described, illustrated in the accompanying drawings, and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings forming a part of this specification, and upon which,

Fig. 1 shows a side elevation of a track laying form of tractor embodying my improvements, part of the chain being broken away to better show my improvements, and

Fig. 2 shows a sectional plan view of the chassis of the tractor shown in Fig. 1 and fitted with my improved equalizing device.

Fig. 3 shows a diagram in perspective of the equalizing means embodied in the present tractor.

Referring in detail to the characters of reference marked upon the drawings, 5 indicates the frame of the tractor, 6 the hood enclosing the motor, 7 the radiator and 8 a gasoline tank that is mounted upon brackets 9 supported upon the above mentioned frame 5. 10 represents a steering wheel mounted upon the post 11 which is journaled in the frame 5 and bracket 12. 13 indicates a seat which is located adjacent to the steering wheel and designed to be occupied by the operator while driving the tractor. 14 represents the motor shaft and 15 the crank for starting the motor. The parts thus far described may be of the usual or any preferred construction and do not form any essential features of the invention since the same are clearly applicable to vehicles of various constructions, and as before stated the invention relates purely to an equalizing device which is located between the frame and front wheels of the machine and prevents the tilting of the machine sidewise or raising the driving wheels and chain entirely off the ground.

It will be noted that the driving wheels 16 and 17 are located under the rear side portions of the machine and are arranged in alignment one with the other being supported more particularly upon spindles that are secured to a portion 18 of the rear axle. 110

Owing to the line on which the section of this view, Fig. 2 is taken, only parts of the axle are shown and to these parts are attached a yoke 19 for supporting the rear 5 part of the equalizing device as will later be more fully described.

The spindles of the front and rear wheels upon each side are connected by two small channel beams 20 and 21, the first one of 10 which is positioned horizontally upon the outside of the wheels and below their spindles and the other upon the inner side of the wheels. A hanger 22 is secured to the 15 top side of the rear portion of these beams to support the same from the spindles of the rear axle while somewhat similar hangers 23 serve to support the forward end of the beams from the forward spindles. The driving wheels 16 and 17 are in the form of 20 sprocket wheels and serve to engage the sprocket chain 24 which may be of the usual or any preferred construction as employed on caterpillar tractor chains, and as shown is made up of a series of links 25 and wide plates 25 mounted upon the outer side thereof and which form a movable tread upon which the wheels run.

The driving wheels as will be noted are 30 more or less rigidly connected with the frame, and the front wheels as before stated are provided with an indirect self-adjusting line of connections whereby the front wheel upon the one side is lowered with relation to the frame in substantially the same proportion that the front wheel on the other side is raised when it runs over a stone or obstruction.

It will be noted that I have provided a 40 depending bracket 26 upon each side of the forward end portion of the frame 5 to support a cross shaft 27 which extends from one side to the other. Two special bell crank levers 28 and 29 are pivotally mounted upon this shaft and are alike in construction 45 and are connected to work independently and loosely upon the shaft and serve in part as a yieldable and equalizing connection between the front wheel and the frame. The lower ends of these levers are each provided with a stud 30 which in turn is connected by a movable link 31 with one side of the inner channel beams 21. The upper end portions of these bell crank levers are 50 provided with a pivotal stud to which the forward ends of the connecting rods 32 are pivotally attached. The inner ends of these rods are slidably mounted in a yoke 33 and are each provided with a spring 34 that is 55 mounted within and between the yoke and the head of the rod, so as to give elasticity and flexibility to the connection. The yokes 33 are pivotally connected to the opposite outer ends of a cross beam 35, the center 60 part of which is pivotally connected to the yoke 19 by means of a link 36.

It will thus be seen that the two side sections of this special construction of equalizing device are respectively positioned within the two sides of the machine and are substantially alike in design and are connected 70 in the rear part of the machine, to the yoke 35 which is hung in the center to a rigid part of the frame of the machine.

From the foregoing construction it should be understood that if the forward front 75 wheel on the near side of the machine is raised by reason of its running upon a stone as is commonly the case when the machine is used in the field, the said wheel would be raised to the height of the stone and thus 80 in turn would raise the forward end of the connected bell crank lever and throw the upper end and connecting rod forward, thereby swinging the yoke 35 upon its pivot in a way to throw the lower end of the other 85 bell crank lever down a corresponding amount thereby equalizing the lift in a way to materially effect the drawing qualities of the tractor, and without raising either of the driving wheels out of operative engagement with the ground. With a four-point 90 suspension, two points of which are equalized, as set forth herein, the action of the bell crank levers will be such as to equally 95 distribute the load to the track laying units, regardless of relative changes in the elevation of said units. This action is illustrated in Fig. 3 where it will be seen that if the track laying unit R falls six inches the connected bell crank lever 28 takes up half this 100 movement by rocking and the other half is taken up by a change in the position of its fulcrum 27, which, in this case, means that the main frame will be lowered three 105 inches. Each rocking movement of three inches on the outer bell crank lever 28 will through the equalizer bar 35 cause the opposite bell crank lever 29 to move a corresponding distance in the opposite direction, and, inasmuch as the track laying unit 110 L can not rise or fall the result is that the fulcrum of the bell crank lever 29 must shift, thus lowering the main frame three 115 inches at this point. The main frame therefore remains on an even keel and the weight thereof is equally distributed on the two track laying units regardless of relative changes in the vertical positions of the latter. Thus there is produced a four-point 120 suspension for the main frame, two of said points being floating with equalizing connections between the floating points.

A further advantage over a three-point suspension is found in the fact that the movement of the bell crank levers is in the same plane as the rocking movement of the track laying units, and the said bell crank levers, forming as they do a direct connection between the track laying units and the main frame, will serve to keep the track 125 130

- laying units in alignment. With a centrally pivoted weight-carrying equalizing bar, such as used in the three-point suspension referred to, the rocking movement of the 5 equalizer bar is in a plane transverse to the rocking movement of the track laying units and the tendency is to throw the track laying units out of alignment. It thus becomes possible to construct a tractor of this type 10 wherein the rigidity and stability of the front ends of the track laying units are comparable to those of the rear ends which are directly pivoted to the main frame.
- Various changes in the construction and 15 arrangement of the several parts herein shown and described may be employed without departing from the spirit of my invention as disclosed in the appended claims.
- In some types of tractors the power plant 20 and transmission housing in and of themselves constitute the main frame. Hence, in the following claims where the term "main frame" is used, it is intended to apply to the suspended weight regardless of its form.
- Having thus described my invention what 25 I claim and desire to obtain by Letters Patent, is—
1. In a vehicle of the class described, the combination with a main frame, of a separate truck at each side including a driving and driven wheel, said truck being pivotally connected to the main frame, bell crank levers pivotally connected to the forward end of the main frame and having one end 30 pivotally connected to a link which in turn is connected to the forward end of the truck frame and equalizing means connecting the other ends of the said links to the main frame.
  2. In a vehicle of the class described, the combination with a main frame, of a pair of truck frames, one arranged at each side of the vehicle, a driving wheel mounted on and supporting the rear part of the truck frame, a driven wheel mounted on the forward end 40 portion of each truck frame, a cross yoke pivotally connected to a fixed part of the rear portion of the main frame, a pair of bell crank levers pivotally connected to the forward part of the main frame, rods connecting the ends of the yoke with one of the ends of the bell crank levers respectively and a link connecting the other end of each bell crank with the forward end of each truck frame.
  3. In a vehicle of the class described, the combination with a main frame, of a pair of driving wheels supporting a part of the frame, a pair of driven wheels supporting 50 another part of the frame, traveling chain treads connecting the two wheels on each side, a separate truck frame connecting the wheels upon each side and hung in part from the spindle of its rear wheel on that side, a pair of brackets secured to the main frame,
  4. A track laying tractor comprising a main frame, a power axle journaled thereon, self-laying track units pivoted concentrically of the power axle, one on each side of the main frame, and a two-point suspension 55 equalizing means at transversely separated points adapted to transmit vertical motion from one self-laying track unit to the other.
  5. In a vehicle of the class described, the combination with a main frame, of a driving and driven wheel upon each side, a separate truck frame connecting the two wheels upon each side, the forward end of the frame being indirectly supported upon one of the forward driven wheels through a bell crank lever pivotally hung from the forward part of the main frame, and having one end pivotally connected to a link which in turn is pivotally connected to the forward end of the truck frame and equalizing means connecting the other ends of the said links to the main frame.
  6. An equalizing suspension for a vehicle, comprising a main frame, a truck frame at each side of the vehicle, a forward and a rear wheel mounted therein, a chain tread connecting the two wheels, one end of the truck frame supporting the rear end of the main frame and the forward end through bell crank levers pivotally connected to the main frame and having one end flexibly and pivotally connected to the forward end of the truck frame, and equalizing means connecting the opposite ends of the bell crank levers to the main frame.
  7. In a track laying tractor, the combination of a main frame, two truck frames located at opposite sides thereof and pivoted thereto, a suspension for the main frame remote from said pivotal connection and including bell crank levers, an equalizer bar pivoted to the main frame, and means connecting said levers with said truck frames and with the opposite ends of said equalizer bar, respectively.
  8. A track laying tractor comprising a main frame, power means thereon, pivoted self-laying track units journaled to the main frame and receiving traction motion from the power means thereon, and a two-point support equalizing means at transversely separated points adapted to transmit vertical motion from one self-laying track unit to the other.
  9. In a track laying tractor, the combina-

- tion of a main frame, two track frames located at opposite sides thereof and pivoted thereto, and a suspension for the main frame remote from said pivotal connection, comprising two rockers each having two arms, means connecting an arm of each rocker to the associated track frame, an equalizer bar pivoted to the main frame, and means which are connected respectively to the other arms of said rockers and with opposite ends of said equalizer bar.
10. In a vehicle, a main frame, a chain track truck mechanism at each side thereof and a load-supporting connection for the main frame comprising a rock arm carried at each side of the main frame and pivotally connected to the adjacent truck mechanism and connecting means between opposite rock arms whereby an upward movement of one of the truck mechanisms will impart a downward movement to the opposite truck mechanism.
11. In a tractor, a main frame, a self-laying track truck mechanism at each side thereof pivotally connected thereto for rocking movement in a vertical plane, an equalizer bar operatively connected with each truck mechanism and pivotally mounted on the main frame on a vertical pivot for rocking movement in a horizontal plane.
12. In a tractor, a main frame, a self-laying track truck mechanism at each side thereof pivotally connected thereto for rocking movement in a vertical plane, an equalizer bar operatively connected with each truck mechanism and pivotally mounted on the main frame on a vertical pivot, and a rock arm included in the connection between the equalizer bar and each truck mechanism.
13. In a tractor construction having separate roller truck frames, and a main frame pivoted at one end thereof, an equalizer mechanism interposed between the forward ends of the roller frames and the main frame comprising a compensating bar centrally pivoted to the main frame, pressure arms carried by the main frame and operatively associated with the opposite roller frames, and connections between said pressure arms and the equalizer bar whereby a swinging movement of one arm will produce a reverse swinging movement of the other.
14. In a tractor, a main frame, a self-laying track unit at each side thereof connected to the main frame for rocking movement in a vertical plane and connections between each unit and the adjacent side of the main frame for transmitting a portion of the weight of the main frame to the said track laying units and means for equalizing the weight transmitted through said connections regardless of the relative vertical positions of the latter.
15. In a tractor, a main frame, a self-laying track unit at each side thereof connected to the main frame for rocking movement in a vertical plane, and equalizing means connecting said track units to the main frame at two transversely separated points and adapted to transmit vertical motion from one track unit to the other.
16. In a tractor, a main frame, a self-laying track unit at each side thereof connected to the main frame for rocking movement in a vertical plane, a rocking member connecting each track unit to the main frame and having movement in a vertical plane parallel with the longitudinal axis of the tractor and an equalizing member connecting the opposite rocking members together.
17. In a tractor of the self-laying track type, a main frame, a self-laying track unit at each side thereof, a four-point suspension means for the main frame, two of said points, one cooperating with each track unit, being floating, and means for equalizing the weight between said floating points at all relative inclinations of the track units.
18. In a tractor, a main frame, a track-laying unit at each side thereof, pivotally connected to the main frame for rocking movement in a vertical plane and equalizing connections between each of said units and the main frame at the end opposite the pivot points, the connections between each track laying unit and the main frame being movable in the same plane as the rocking movement of the track laying unit and serving to preserve alignment of the latter.
